UNITED STATES PATENT OFFICE

WILLIAM S. LYHNE, OF KNOXVILLE, TENNESSEE, ASSIGNOR TO THE FULTON SYLPHON COMPANY, OF KNOXVILLE, TENNESSEE, A CORPORATION OF DELAWARE

DESIGN FOR A PORTABLE VENDER

Application filed September 10, 1930. Serial No. 36,923. Term of patent 14 years.

To all whom it may concern:

Be it known that I, WILLIAM S. LYHNE, a citizen of the United States of America, and a resident of Knoxville, Tennessee, have invented a new, original, and ornamental Design for Portable Venders, of which the following is a specification, reference being had to the annexed drawings, forming a part thereof.

In the drawings:

Fig. 1 is a side elevational view of a portable vender incorporating my new and ornamental design;

Fig. 2 is a plan view of the portable vender illustrated in Fig. 1, and

Fig. 3 is an end elevational view of the portable vender illustrated in Figs. 1 and 2. I claim.

The ornamental design for a portable vender as shown.

In testimony whereof I have signed this specification.

WILLIAM S. LYHNE.
